R. R. CUMMINS ET AL

BELT SHIFTING MECHANISM

Original Filed June 20, 1919

UNITED STATES PATENT OFFICE.

ROBERT R. CUMMINS AND ROBERT W. KREMER, OF CLEVELAND, OHIO, ASSIGNEES TO THE KREMER-CUMMINS MACHINE COMPANY, OF CLEVELAND, OHIO, A CORPORATION OF OHIO.

BELT-SHIFTING MECHANISM.

Application filed June 20, 1919, Serial No. 305,606. Renewed November 22, 1923.

To all whom it may concern:

Be it known that we, ROBERT R. CUMMINS and ROBERT W. KREMER, citizens of the United States, and residents of Cleveland, county of Cuyahoga, State of Ohio, have jointly invented a new and useful Improvement in Belt-Shifting Mechanism, of which the following is a specification, the principle of the invention being herein explained and the best mode in which we have contemplated applying that principle, so as to distinguish it from other inventions.

The present improvements, relating, as indicated, to belt shifters, are particularly directed to the improvement and simplification of mechanical belt shifters, in which the belt of a lathe or other machine tool may be shifted along the various steps of the driving and driven pulleys, without requiring the operator's hand to touch the belt. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a front elevation illustrating the attachment of our improved belt shifter to the driving and driven pulleys of a lathe, Fig. 2 is a transverse section through said shifter; Fig. 3 is a view in perspective of the rack member; Fig. 4 is a transverse section through the rack and pinion; Fig. 5 is a plan view of the upper belt-shifting loop and slide; Fig. 6 is a plan view of the lower loop; Fig. 7 illustrates a detail of construction; Fig. 8 is a section illustrating a modification of the construction; Fig. 9 is a side elevation of our apparatus; and Fig. 10 is a view of a modification.

In this type of device it is customary to support a rack below and parallel with the driving shafting and the driving pulley, and to then operate a movable element along this rack, with the movable element carrying a belt-engaging and shifting loop. It is also common practice in the shifters now in use to provide a similar arrangement to

be attached to the head stock of the lathe or other machine tool on which it is used, and to thus give two mechanically moved elements, each of which engages and shifts the belt, one along the upper pulley and one along the lower. The disadvantage of this type of shifters is that they involve considerable mechanical complication, are expensive to manufacture, and require considerable labor in installation; all of which faults are sought to be avoided in the present improvements.

In our improved shifter a channel or plate 1 is mounted parallel to, and below, the steps 2, 3 and 4 of the upper or driving pulley. This channel is provided at either end with an inset block 5, having a rounded extension 6 and these rounded extensions are set into apertured bosses 7, depending from a U-shaped support 8, which is adjustably mounted upon a horizontal rod 9, which is in turn supported by pipe fixtures 10 from the ceiling 11. After the channel has thus been mounted in the bosses 7 it may be turned to any desired angle to bring its upper and lower surfaces at right angles to the plane of a belt 12, which passes over one of the driving pulleys 2, 3 and 4 for the purposes which will later be described, and may be locked in this position by means of set screws 13. The lower edge of one of the flanges 14 of the channel member 1 is formed with a series of grooves or recesses to constitute teeth, and is engaged with a pinion 15 rotatably mounted in a carriage 16 which is slidable longitudinally upon the channel 1 and is operated to thus move by rotation of the pinion 15 by means of a depending handle or rod 17.

Slidably mounted in a slot in the lower portion of the carriage 16, and movable transversely the movement of said carriage, is a rod 18, carrying at its upper end a pivoted belt-engaging loop 19. This belt-engaging loop is formed of two separate portions removably secured together and provided with complementary semi-oval recesses 20 in their adjacent sides, and is provided with extending bosses 21 fitted on either side of an enlarged end 22 on the rod 18. A bolt 23 passes through the enlarged end 22 and the bosses 21 and forms the axis about which the shifting loop may be swung, while it may be clamped in any desired

position by means of a set screw 24 in the enlarged end 22 and other set screws 25 in the bosses 21 in order to properly position the belt-shifting loop about the belt, irrespective of the angle at which the belt is mounted, which of course will vary considerably with different machines.

The operation of the upper belt-shifting loop just described, will be readily understood from the foregoing description. To shift the belt 12 from any one of the steps 2, 3 and 4 to the next adjacent step it is only necessary to turn the handle 17 to rotate the pinion 15, and thus move the carriage 16 along the channel member 1. This will of course move the belt-shifting loop transversely along the pulleys 2, 3 and 4 and will push the belt enclosed within the loop 19 from one step to the next.

Extending downwardly from the carriage 16 are two apertured bosses 30, through which extends a rod 31, upon one end of which is pivotally mounted a bracket 32. The lower portion of this bracket is provided with spaced apertured lugs 33, between which is pivotally mounted a coupling 34 in which there may be removably inserted a rod 35, having at its lower end a laterally extending belt-shifting loop 36. On this second loop 36 is mounted a handle 37 and the loop will engage over the opposite side of the belt 12 as the belt leaves one of the series of driven pulleys 38, 39 and 40, which represent the driven pulleys of a lathe or other machine tool. In ordinary practice a lathe is mounted almost vertically below the line shaft from which it is driven, and thus both sides of the driving belt are vertical, or nearly so. There is ordinarily a slight angle given to this belt and this will necessitate the lower loop 36 resting against the belt 12, but as the inner sides of the belt-shifting loop are perfectly smooth and are bevelled or rounded away from the belt, this continuous friction between the belt and the loop has been found not to injure the belt in any way.

It is possible, however, to avoid the above action if desired, and in Figure 8 we show a single slidable rod 41 mounted in the carriage 16, and movable transversely the movement of said carriage, and carrying an upper belt-shifting loop 42 on one end and a depending rod 43 for carrying the lower loop on the other end. In this construction, as the rod 41 slides across the carriage to accommodate the various vertical positions, which the belt 12 assumes, by reason of the different diameters of the pulleys 2, 3 and 4, the rod 43 and the lower loop carried thereby, will be correspondingly moved in the same direction. Thus, if the upper loop 42 is pulled over beneath the outer surfaces of the largest

upper pulley 2, the lower belt-shifting loop carried on the rod 43 is pulled over an equal distance, and will thus be found to be in exactly the proper position to receive the belt 12 as it leaves the smallest pulley 38 on the lathe. By this construction it is possible to compensate and adjust the various positions which are required for the two belt-shifting loops without any actual continuous contact between the loops and the belt.

In operation a shift of the belt 12 from a smaller to a larger size of pulley in the upper pulleys is accomplished by first moving the handle 37 in a direction to throw off the belt 12 from the lower pulley on which it is running. The belt is thus slackened and the upper loop may then be actuated by the handle 17 to force the belt on to the next higher upper loop. In shifting in the reverse direction the upper loop is first actuated by the handle 17 to throw off the belt 12 from the pulley on which it is running, and after it has been thrown on to the next smaller pulley the handle 37 is used to force the belt on to the next larger lower pulley.

In some cases where a very wide driving belt is used the operating handle 17 is brought so close to the belt that it cannot be conveniently operated with the ordinary mounting. In this case it is only necessary to shorten the supports 10 at the right end of the rack 5, as seen in Fig. 1. This mounting of the rack at a slight angle to the common axis of the pulleys 2, 3 and 4 will throw the handle 17 away from the belt, causing it to stand several inches from the belt at the lower end of the handle and leaving plenty of room for the operator to manipulate it.

The advantages of the present mechanism are its obvious simplicity and ease of installation, while a very considerable economy is effected by mounting both upper and lower shifting loops from a single support, which is of course the channel member 1. This handle eliminates any need for a lower support, which has been universally used in such mechanisms, with the attendant extra cost of manufacture and of installation.

It will be evident that the carriage 16 is ordinarily directly between the two sides of the belt 12, and as sometimes the pulley size is so small that the two sides of the belt are brought very close, or it is necessary to provide some means for assembling the apparatus without letting the belt work against the front of the carriage and of the members carried thereon. Such an assembly is shown in Fig. 10, in which the enlarged end 22 on the rod 18, and the lugs 21 on the belt shifting loop 20 are mounted side by side instead of in the

manner in Fig. 5, in order to offset the belt-shifting loop 19 with respect to the member 18 and the carriage 16. This assembly brings the carriage outside of the space between the two sides of the belt and it is then of course possible to similarly offset the lower belt-shifting loop to correspond to the vertical plane of the upper loop. This assembly is secured, however, without any change in the construction and by merely using a longer bolt 60 for fastening together the upper belt-shifting loop and the enlarged end 22 on the rod 18.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a device of the character described, the combination with two aligned reversely mounted step pulleys and a continuous shiftable belt operatively connecting the same, of a guideway mounted adjacent to one of said pulleys and substantially parallel with the axis thereof, a carriage movable along said guideway, a belt shifting loop mounted on said carriage and engaging over the adjacent belt, a second belt-engaging and shifting loop also supported from said carriage, and separate means adapted to actuate said loops to shift said belt on said two pulleys.

2. In a device of the character described, the combination with two aligned reversely mounted step pulleys and a continuous shiftable belt operatively connecting the same, said pulleys being mounted at different vertical levels, of a guideway mounted adjacent to the upper of said two pulleys and substantially parallel with the axis thereof, a carriage movable along said guideway, a belt-shifting loop mounted on said carriage and engaging over the adjacent belt, and a second belt-engaging loop depending vertically from said carriage and engaging over said belt adjacent said vertically lower pulley.

3. In a device of the character described, the combination with two aligned reversely mounted step pulleys and a continuous shiftable belt operatively connecting the same, said pulleys being mounted at different vertical levels, of a guideway mounted adjacent to the upper of said two pulleys and substantially parallel with the axis thereof, a carriage movable along said guideway, a member slidably mounted on said carriage to move transversely thereof, a depending rod carried on said member and extending to a point adjacent said lower pulley, belt-engaging and shifting loops mounted on said member and said rod, and means per-

mitting independent operation of said loops to shift said belt on said upper and lower pulleys.

4. In a device of the character described, the combination with two aligned reversely mounted step pulleys and a continuous shiftable belt operatively connecting the same, said pulleys being mounted at different vertical levels, of a guideway mounted adjacent to the upper of said two pulleys and substantially parallel with the axis thereof, a carriage movable along said guideway, a belt-engaging and shifting loop slidably mounted transversely in said carriage to allow movement of said loop to compensate for the different positions of said belt when on different steps of said upper pulley, a depending rod pivotally mounted on said loop to swing in a plane parallel to the axis of said lower pulley, and a second loop carried on said rod and engaging over said belt adjacent said lower pulley, and separate means adapted to actuate said belt-shifting loops independent of each other.

5. In a device of the character described, the combination with two aligned reversely mounted step pulleys, and a continuous shiftable belt operatively connecting the same, said pulleys being mounted at different vertical levels, of a guideway mounted adjacent to the upper of said two pulleys and parallel with the axis thereof, a carriage movable along said guideway, a belt-engaging and shifting loop slidably mounted transversely in said carriage to allow movement of said loop to compensate for the different positions of said belt when on different steps of said upper pulley, a depending rod pivotally mounted on said loop to swing in a plane parallel to the axis of said lower pulley, and a second loop carried on said rod and engaging over said belt adjacent said lower pulley, and depending means adapted to actuate said carriage along said guideway to cause said loop to shift said belt on said upper pulley.

6. In a device of the character described, the combination with two aligned reversely mounted step pulleys and a continuous shiftable belt operatively connecting the same, said pulleys being mounted at different vertical levels, of a guideway mounted adjacent to the upper of said two pulleys and parallel with the axis thereof, a carriage movable along said guideway, a belt-engaging and shifting loop slidably mounted transversely in said carriage to allow movement of said loop to compensate for the different positions of said belt when on different steps of said upper pulley, a depending rod pivotally mounted on said loop to swing in a plane parallel to the axis of said lower pulley, and a second loop carried on said rod and engaging over said belt adjacent said lower pulley, and depending

means adapted to actuate said carriage along said guideway to cause said loop to shift said belt on said upper pulley, and a handle on said lower loop for moving the same.

7. In a device of the character described, the combination of an inverted channel member, said channel having a series of notches formed in one flange thereof, a carriage movable along said channel, and a pinion on said carriage engaging in said notches in said channel.

8. In a device of the character described,

the combination of a support mounted substantially parallel with the axis of a driving pulley, a carriage movable along said support, a rod mounted on said carriage to move transversely to the movement of said carriage, and a belt-shifting loop mounted on said rod, but in an offset plane, whereby said loop and rod will lie in different vertical planes.

Signed by us, this 16th day of June, 1919.

ROBERT R. CUMMINS.
ROBERT W. KREMER.
